CLAIM

The ornamental design for a rear cap for a motor vehicle, as shown and described.

DESCRIPTION

FIG. 1 is a left side view of a rear cap for a motor vehicle according to our novel design. The right side being a mirror image thereof;

FIG. 2 is a perspective view from the left rear side and above of the rear cap for a motor vehicle according to our novel design; and,

FIG. 3 is a rear view of a rear cap for a motor vehicle according to our novel design.

Features shown in broken lines depict the environment and do not form part of the claimed design.
